CLAIM

The ornamental design for a baitcast fishing reel body, as shown.

DESCRIPTION

FIG. 1 is a perspective view, illustrating the left side, rear and top, of a baitcast fishing reel body showing the new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a rear elevational view thereof.

The broken lines showing of environment in the drawings are for illustrative purposes only and form no part of the claimed design.
